UNITED STATES PATENT OFFICE.

CHARLES BARNES, OF DAYTON, KENTUCKY.

AUTOMATIC FIRE-EXTINGUISHER.

SPECIFICATION forming part of Letters Patent No. 319,774, dated June 9, 1885.

Application filed April 2, 1885. (No model.)

To all whom it may concern:

Be it known that I, CHARLES BARNES, a citizen of the United States, and a resident of Dayton, in the county of Campbell and State 5 of Kentucky, have invented certain new and useful Improvements in Automatic Fire-Extinguishers, of which the following is a specification.

My invention is an improved distributor for 10 automatic fire-extinguishers. Its object is a compact reliable device that costs but little in labor and material to construct, requires no skilled labor to fit to its place, and while being very sensitive to heat is not liable to get out 15 of order. These objects are attained by the means illustrated in the accompanying drawings, in which—

Figure 1 is a radial section of the shell and a longitudinal elevation of the valve and valve-rod, the parts being shown detached. Fig. 2 20 is a similar view of the shell cast in one piece, with the valve in place, which is also shown in elevation here. Fig. 3 is a similar view of the shell shown in Fig. 2, with the valve shown 25 in Fig. 1, and a different means for adjusting and holding the valve to its seat.

Referring first to Fig. 1, the cylindrical shell A, cap a, neck a', and brackets a² are cast in one piece. When the shell is cast, the cylindrical body meets the cap a in a straight line, and the line connecting the outer rim of the cap with the cylindrical body is a slightly-obtuse angle, to permit the shell to be drawn 30 easily from the mold. After the shell is molded it is centered in the lathe and the upper side dished out, as shown, cutting entirely through the cylindrical shell to form the discharge-port, and thus leaving the cap, neck, and shell connected by the brackets a² only. 35 On top of the valve B is a rubber cup-valve, C, which enters the piece D, by which the distributor is secured to the end of the discharge-pipe. Its upper end, d, is screw-threaded for this purpose, while its lower end, d', is threaded 40 to screw into the top of the cylinder A. A wrench-seat, d², is left between the threaded parts for the purpose of securing the distributor together and to the end of the discharge-pipe. The valve-stem b is transversely perforated at its lower end, as is also the neck a', 45 to receive a pin of fusible material. The parts 50

are fitted together by passing the valve-stem through the shell A and into the neck a' until the transverse perforations in the stem and neck register. The fusible pin is then passed 55 through the neck and stem, and the piece D is then screwed into the piece b until the valve B is brought against its seat in the end of the piece D, when the distributor is ready to be attached to the discharge-pipe.

In Fig. 2 I have shown the whole distributor cast in one piece. The same cup-valve, C, is used; but instead of the valve B the upper end of the valve-stem b is provided with a rounded head, which enters the bore in the part D. 60 When the water is turned into the pipes, the rubber cup-valve will pack tightly around this and prevent leakage until the pin b' is fused and the valve thrown out of its orifice. The form shown in Fig. 3 differs in having the cap 70 a centrally perforated, screw-tapped, and a plug, E, provided with valve adjusting and releasing attachments connected to it, fitted to the opening. The attachments consist of the bar F, which is rigidly secured to the plug E, 75 and has one of its ends, f, turned down and slotted to form one leaf of a hinge. The opposite leaf of the hinge is the upturned end of the hinged lever G. The opposite end, f', of the bar F is turned up and vertically slotted 80 to admit the upturned end g' of the hinged lever G. This end of the lever G is transversely perforated, the perforation registering with transverse perforations in the end f' of bar F, 85 in the position shown in the drawings, so that when the fusible pin b' is passed through these perforations the parts will be held in the position shown until the pin is fused by heat in case of fire. The plug E and bar F are perforated to pass the valve-stem b, which rests 90 upon the end of a screw, H, which is tapped through the lever G. By this screw the valve is tightened and held to its seat on the inner end of the tubular neck of piece D. It will be seen that in case of fire the pin b' will be fused, 95 the valve released, and the flow of water turned into the shell A, forced through the slot dividing it and the cup a, deflected upwardly and laterally in a thin sheet or spray, and in this manner discharged upon the fire.

The forms of valve and valve-releasing devices are not broadly claimed herein, as the

same are patented to me and shown in my pending application; and it is evident that other well-known forms of valve and valve-releasing devices may be used with my distributor herein shown; and it is also evident that the shell A and deflecting-cap α may be cast separately, with the brackets attached to either piece, for securing the parts together, as shown in the drawings.

10. What I claim as new, and desire to secure by Letters Patent, is—

1. In an automatic fire-extinguisher, the combination, substantially as specified, of the distributor-shell A, deflecting-cap α , and brackets 15 α^2 , with a valve extending through the distributor shell and cap and held to its seat by fusible material.

2. A distributor for automatic fire-extinguishers, consisting of the shell A, cap α , neck α' , brackets α^2 , cast in one piece with the piece 20 D, for securing the distributor to the discharge-pipe, and a valve passing through the distributor-shell and held to its seat by fusible material.

3. The combination of the shell A, cap α , 25 neck α' , and brackets α^2 , cast in one piece with the piece D, with valve C and stem b , passing through the shell and neck and secured in its place by fusible pin b' , substantially as specified.

CHARLES BARNES.
